(57) **CLAIM**

The ornamental design for a backpack with a concealed mirror, as shown and described.

DESCRIPTION

FIG. 1 is a front, top and left side perspective view showing our new design, with the top flap down or closed.

FIGS. 2-7 are views of the backpack with a concealed mirror as it is shown in FIG. 1, wherein:

FIG. 2 is a front view.

FIG. 3 is a back view.

FIG. 4 is a left side view.

FIG. 5 is a right side view.

FIG. 6 is a top view.

FIG. 7 is a bottom view.

FIG. 8 is a front, top and left side perspective view showing the backpack with a concealed mirror of FIGS. 1 to 7 with the top flap up or open.

FIGS. 9 to 14 are views of the backpack with a concealed mirror as it is shown in FIG. 8, wherein:

FIG. 9 is a front view.

FIG. 10 is a back view.

FIG. 11 is a left side view.

FIG. 12 is a right side view.

FIG. 13 is a top view; and,

FIG. 14 is a bottom view.

Dotted lines indicate unclaimed subject matter.
